United States Patent Office

Des. 196,277
Patented Sept. 10, 1963

196,277

PHOTOGRAPHIC PRINT CONTAINER OR SIMILAR ARTICLE

Edwin Land, Cambridge, Mass., assignor to Polaroid
Corporation, Cambridge, Mass., a corporation of Delaware

Filed Oct. 19, 1962, Ser. No. 72,193

Term of patent 14 years

(Cl. D61—1)

FIG. 1

FIG. 2

FIG. 3

FIGURE 1 is a perspective view of a photographic print container or similar article, showing my new design;

FIG. 2 is a side elevational view thereof, showing the side opposite that seen in FIGURE 1;

FIG. 3 is a right-end elevational view thereof;

FIG. 4 is a left-end elevational view thereof; and

FIG. 5 is a bottom plan view thereof.

I claim:

The ornamental design for a photographic print container or similar article, substantially as shown.
